UNITED STATES PATENT OFFICE.

EDWARD E. GOLD, OF NEW YORK, N. Y.

DESIGN FOR A STEAM-TRAP CASING.

SPECIFICATION forming part of Design No. 31,444, dated August 22, 1899.

Application filed July 7, 1899. Serial No. 723,120. Term of patent 14 years.

To all whom it may concern:

Be it known that I, EDWARD E. GOLD, a citizen of the United States, residing at New York, in the borough of Manhattan, county 5 and State of New York, have invented a certain new and original Design for Steam-Trap Casings, of which the following is a specification.

The present design relates to casings or 10 outer shells for steam-traps. My design is shown in the accompanying drawing.

My design comprises an upper member A, an intermediate member B, and a lower member C. The intermediate member B is cylindrical, while the upper member A is of the shape shown, having the usual hexagonal portions *a* and *b*. The lower member C is mainly conical, as shown, being formed with a cylindrical portion *c* at its top where it joins the

member B. Near its bottom it has a flaring 20 portion *d* and at its bottom is surrounded by a band *e*.

That which is distinctive in my design is the addition to the usual upper and intermediate members A and B of the lower member 25 C, which is made conical and has the convex flaring projection or flange *d*.

I claim—

The described design for a steam-trap casing, as shown in the accompanying drawing. 30

In witness whereof I have hereunto signed my name in the presence of two subscribing witnesses.

EDWARD E. GOLD.

Witnesses:

ARTHUR C. FRASER,
FRED. WHITE.
